(57) **CLAIM**

The ornamental design for a digital pathology apparatus, as shown and described.

DESCRIPTION

FIG. 1 is a front-right perspective view of a digital pathology apparatus according to the present invention;

FIG. 2 is a back-left perspective view thereof;

FIG. 3 is a front side view thereof;

FIG. 4 is a back side view thereof;

FIG. 5 is a left side view thereof;

FIG. 6 is a right side view thereof;

FIG. 7 is a top side view thereof; and,

FIG. 8 is a bottom side view thereof.

The broken lines immediately adjacent the shaded areas represent the bounds of the claim, while all other broken lines are directed to environment and are for illustrative purposes only; the broken lines form no part of the claimed design.
